United States Patent Office

Des. 178,486
Patented Aug. 14, 1956

178,486

TIRE

James G. Balmer, Jr., and Robert G. Smith, Birmingham,
Mich., assignors to United States Rubber Company,
New York, N. Y., a corporation of New Jersey

Application July 5, 1955, Serial No. 36,811

Term of patent 14 years

(Cl. D90—20)

Fig. 1

Fig. 2

Fig. 1 is a perspective view of a tire showing our new design, it being understood that the full line tread portion is repeated throughout the circumference of the tire shown by means of broken lines; and

Fig. 2 is an enlarged and fragmentary perspective view of the tire, showing our new design.

The dominant feature of our design consists in the portions shown in full lines.

We claim:

The ornamental design for a tire, substantially as shown and described.
